UNITED STATES PATENT OFFICE.

ELMER DUCHARME, OF KANKAKEE, ILLINOIS.

VALVE HOLDER.

Application filed February 25, 1927. Serial No. 171,058.

This invention relates to a valve holder for use in temporarily holding the valves of an internal combustion engine during overhauling thereof, but susceptible for holding or retaining other articles.

It is an object of this invention to provide an improved sectional valve holder for protecting and holding the valves in proper order during the overhaul period as while in grinding the valves. The valves are relatively delicate parts, each of which should be returned to its own valve seat to insure proper seating and to avoid the necessity of, and risk of injury involved in stamping numbers on each valve for identifying the valves; and also to protect the valves from injury if they are laid down among the tools; it, therefore, is an object of this invention to provide a compact and convenient holder therefor.

Other and further important objects of this invention will be apparent from the disclosures in the drawings and specification.

This invention (in a preferred form) is illustrated in the drawings and hereinafter more fully described.

On the drawings:

Figure 1 is a fragmentary side elevation of a vehicle showing a device embodying the features of this invention in use thereon.

Figure 2 is a fragmentary top plan view of the device.

Figure 3 is an enlarged fragmentary section on the line III—III of Figure 1.

Figure 4 is a section on the line IV—IV of Figure 3.

Figure 5 is a section on the line V—V of Figure 3.

As shown on the drawings:

The parts of a vehicle shown in Figure 1 comprise the engine 10, radiator 11 and cowl 12 together with three engine valves 13 positioned in a device embodying the features of this invention which may be supported across the radiator and cowl for the convenience of the mechanic working on the engine.

The device of this invention comprises a box section hollow tube made up of a number of sections 14, one end 15 of each section being of reduced size to enter the full size end of the next section to make a readily knocked down holder suitable for carrying in a tool kit.

Each section is provided with a number

of aligned apertures 16 in both the top and bottom walls thereof of a size accommodating the largest valve stems likely to be encountered. As such large apertures would not retain smaller valves when placed therein, means are provided to frictionally engage the valve stems, comprising a coil spring 17 in each section mounted under a slight tension at the ends on pins 18, the spring being positioned to partly cover each valve aperture 16. Between each pair of apertures 16 an indentation 19 is pressed into the side wall of the section to contact the spring in order that each valve stem will receive the same pressure from the spring regardless of the presence or absence of valve stems in adjacent apertures.

From the foregoing description taken in connection with Figures 3 and 5, it will be evident that a valve stem can be inserted in any aperture 16 thus distorting or shoving the spring 17 to one side and in turn causing the spring to press the valve stem against the sides of the apertures to frictionally retain the valves in the holder even though the latter might become upset.

It will thus be seen that I have provided a simple and improved valve holder that can be placed in a mechanic's tool kit and only enough sections thereof need be assembled to suit the particular job in hand as the number of valves on different engines ordinarily varies from 8 to 24.

I am aware that many changes may be made and numerous details of construction may be varied through a wide range without departing from the principles of this invention and I, therefore, do not purpose limiting the patent granted hereon, otherwise than necessitated by the prior art.

I claim as my invention:

1. A valve holder comprising a hollow tube of rectangular cross section having a series of aligned apertures on opposite faces thereof adapted to receive valve stems, a coil spring mounted longitudinally within said tube and extending partly across the axis of said apertures whereby the insertion of a valve stem therethrough will displace said spring, and indentations in the wall of said tube at right angles to the axis of said apertures and midway between adjacent sets thereof, said indentations being adapted to contact said spring and assist in gripping valve stems inserted in said apertures.

2. A device of the class described compris-

ing a plurality of interfitting members, each member being of rectangular section and having a number of aligned apertures in opposite sides thereof, a coil spring longitudinally mounted within each member adapted to be distorted by the insertion of articles through said aligned apertures, and abut-

ments between each pair of aligned apertures adapted to engage the spring and isolate the sections thereof to increase the holding power thereof. 10

In testimony whereof I have hereunto subscribed my name.

ELMER DUCHARME.
